RIVETING MACHINE

Thomas H. Speller, Williamsville, and Frederick A. Pettis, Buffalo, N. Y., assignors, by direct and mesne assignments, to General Riveters, Inc., Buffalo, N. Y., a corporation of New York

Application June 28, 1945, Serial No. 602,092

11 Claims. (Cl. 29—26)

1

Our invention relates in general to riveting machines, and in particular to that type of machine in which a hole for the rivet is first drilled into the workpiece, after which a rivet is fed into the hole where it is held while being upset by pressure means.

The principal object of our invention has been to provide a machine of this nature by which the above results may be accurately accomplished in sequence and by automatic means.

Another object has been to provide a machine having means for rigidly holding the workpiece in place while it is being drilled and/or countersunk.

A further object has been to provide means for feeding a rivet to the pre-drilled hole.

Another object has been to provide a laterally movable bucking tool with means for bringing it into coaxial relation with the head of the rivet to be upset.

Moreover, our device is provided with means whereby the drill ram may be locked axially to cooperate with said bucking tool during the riveting operation.

Furthermore, our device is provided with a riveting ram carrying a riveting anvil having a pressure rail, the latter serving to move the workpiece to a place of support and hold it in position while being drilled, and the former, upon subsequent axial movement, serving to upset the rivet.

The above objects and advantages have been accomplished by the device shown in the accompanying drawings, of which:

Fig. 1 is a side elevation of our complete machine;

Fig. 2 is an end elevation of the same;

Fig. 3 is an enlarged sectional elevation of the drilling unit;

Fig. 4 is an enlarged front elevation of the portion of the machine shown in Fig. 3;

Fig. 5 is a fragmentary sectional elevation taken on line V—V of Fig. 4;

Fig. 13 is a fragmentary sectional view of the riveting ram taken on line XIII—XIII of Fig. 14;

Fig. 14 is a fragmentary sectional plan view of the riveting ram taken on line XIV—XIV of Fig. 13;

Fig. 15 is a line diagram of the electric controls and circuits preferably employed in carrying out our invention; and

Fig. 16 is a diagrammatic view of the selector switch used with our device.

As shown in Fig. 1, our riveting machine comprises a body frame 15 of general C shape having an upper leg 16 and a spaced lower leg 20, thereby providing the throat 21 of the machine. The forward end of the upper leg has the drilling unit 22 attached thereto, and the lower leg supports the riveting unit 23.

The drilling unit of our device comprises a ram head 24 suitably secured to the forward vertical face of the upper leg 16 of the frame. A top plate 25 is extended across the top of the head. The head is formed with a vertically arranged cylindrical bore 26 for the reciprocal support of the drill ram 30. This ram is formed with an upper bearing portion 31 and a reduced lower portion 32, whereby a shoulder 33 is provided for engagement with a detent arm 34 carried by a detent plate 35. The detent arm and plate are pivotally secured to the head at 36, and the forward end 37 of the arm is disposed in a slot 40 formed in the head and is extended inwardly in the path of the drill ram to limit its downward movement. A helical spring 41 is carried by the head and is located under the free end of the plate 35, whereby the plate and attached detent will be urged in a clockwise direction. A stop screw 42 is carried by the upper end of the detent plate and has its inner end bearing against the ram head to resist the action of the spring 41. By means of this adjusting screw the end 37 of the detent arm may be adjusted so as to accurately limit the downward travel of the drill ram 30 and the depth of the countersunk hole.

Mounted in the lower end of the bore 26 of the ram head is the upwardly projecting cylindrical portion 43 of a presser foot 44. This presser foot is suitably secured in place and is provided with two downwardly extending spaced arms 45 connected at their lower ends by a pad 46 for engagement with the upper surface of the workpiece. The upwardly extending portion 43 of this presser foot is provided with a suitable bore 50 for the bearing support of the reduced portion 32 of the drill ram. The presser foot provides a support for the workpiece while it is being drilled.

and countersunk, and the workpiece is preferably forced upwardly and held in contact therewith by means of the initial operation of the riveting unit 23 of the device, to be hereinafter described.

A lifter rod stud 51 is carried by the portion 31 of the drill ram and is extended radially through a vertical slot 52 formed in the cylindrical portion of the ram head. Secured to the outwardly extending end of this stud is the lower end of a lifter rod 53. This rod has an upper end 54 preferably bent at right angles and secured to the upper end of the plunger rod 55 of the drill ram operating cylinder 56. This cylinder is mounted preferably behind the cylindrical portion of the head and has its lower end attached to the flange 60 of the ram head by means of a pivot 61. Fluid pressure supplied to either end of this cylinder causes the ram to move downwardly or upwardly, as will be hereinafter more fully described. In order to limit the upward movement of the plunger rod 55, a bumper 62 is provided. This bumper is carried by the top plate 25 and straddles the plunger rod 55. It is provided with a bumper stud 63 which is slidably mounted in the bumper and has its head 64 extending downwardly in the path of travel of the plunger rod. The stud is pressed downwardly by means of a helical spring 65.

Working in synchronism with the detent arm 34 is a limit switch 115. This limit switch is carried by a bracket 66 mounted for oscillation upon a pin 71 and carried by a pedestal 70 secured to the flange 60 of the drill head. The pin 71 is offset in relation to the bracket 66, and a helical spring 72 is arranged under the overhanging arm 73 of the bracket serving to urge the switch in a clockwise direction of rotation, as viewed in Fig. 8. An adjusting block 74 is carried by the arm 73 and has an inclined surface 75 for engagement with an adjusting screw 76 carried by the face plate 77 of the drill head. As hereinbefore described, the detent arm is adjusted so as to countersink the rivet hole to the proper depth, and then the limit switch 115 is adjusted by means of the screw 76 to close slightly in advance of the point where the ram reaches this predetermined position. The switch 115 is operated by an adjusting rod 80 which is carried by the switch operating arm 81. This arm is secured to the lifter rod stud 51 and is therefore moved with the drill ram. The engagement of the adjusting rod 80 with the switch 115 serves, through the circuits to be herein-after described, to interrupt the downward movement of the drill ram at a predetermined place in its travel and to cause it to move upwardly to its initial position.

Extending through the drill ram 30 is a drill shaft 82. This shaft is rotatably supported in suitable anti-friction bearings mounted in the drill ram, and carries a chuck 83 at its lower end. This chuck is designed to receive and hold a drill and countersink 84. The drill shaft is driven by means of a pulley 85 which is suitably mounted upon a stationarily arranged stud 86, carried by the top plate 25. This pulley is preferably mounted upon suitable anti-friction bearings (not shown) and is held against axial movement. Since the drill shaft 82 moves up and down with the drill ram 30, means, preferably in the form of a key and keyway, are provided which permits the shaft to be driven by the pulley at any point throughout its axial travel. The pulley 85 is driven by means of a belt 90 which passes over a pulley 91 carried by a jack shaft 92.

This jack shaft is suitably mounted in a support 93 carried by the top plate 25, and a pulley 94 is mounted on the lower end thereof. The pulley 94 is driven by means of a belt 95 which passes over a drive pulley 96 mounted on the shaft of a drive motor 100. As shown in Fig. 1, this motor is preferably mounted within the body frame of the device.

According to our invention, after the hole has been drilled and/or countersunk in the workpiece, a rivet is fed to and placed within the pre-drilled hole. Synchronously with the placement of the rivet, a bucking tool is brought into coaxial relation with the rivet to force the rivet into the hole and to act as a bucking tool for the riveting operation. This is accomplished by providing a rivet locator 101 which is carried at the outer end of a locator leg 102. This leg is mounted upon the lower end of a pivot shaft 103 for oscillation therewith. This shaft is rotatably mounted within a pivot sleeve 104 which is mounted for oscillation within a suitable bearing carried by the flange 60 of the head. The rivet locator is provided with suitable rivet holding fingers 105 which are pivotally mounted upon a stud 106 and held in their normally closed position by means of a spring 107. A rivet-receiving aperture 110 is formed between the fingers, and the outer ends of the fingers are separated when a rivet is being discharged from between them. The locator is provided with an aperture 111 which registers with the apertures 110 formed by the fingers 105. In the normal inactive position, the aperture 111 of the locator is accessible for receiving single rivets fed thereto either manually or by any suitable automatic means. Mounted about the pivot sleeve 104 is a bucking cap sleeve 113. A bucking cap 114 is carried by this sleeve and has its leg 115 secured thereto by means of a bolt 116. The bucking cap is designed to move vertically with respect to the locator and in carrying out our invention, the sleeve 113 is therefore mounted upon the pivot sleeve 104 so as to permit relative axial movement only. The parts are rotated together in unison by means of the bolt 116 which has its end passing into a slot 120 formed in the pivot sleeve 104. A helical spring 121 is mounted about the bucking cap sleeve and has one of its ends bearing against the leg 115 of the cap and its other end bearing against the leg 102 of the pivot locator, whereby to urge the bucking cap sleeve 113 upwardly and to retain it in its normal inactive position. A pivot locator arm 122 is carried at the upper end of the pivot shaft 103, and a bucking cap arm 123 is secured to the upper end of the pivot sleeve 104.

When a rivet is to be placed in a previously drilled hole, it is necessary that both rivet locator 101 and bucking tool 131 be brought to a coaxial position in relation to the drill ram and be disposed between the ram and the rivet. It is necessary, however, in order to conveniently feed a rivet into the rivet locator, that the locator be swung outwardly a greater distance than the bucking cap as clearly shown in Fig. 10. Since both of these devices are operated by means of a single operating cylinder 124, it is necessary that the same amount of operative movement produces a greater amount of swing of the locator than that of the cap. In order to accomplish this, the pivot locator arm 122 is shorter than the bucking arm 123, whereby to compensate for the difference in the necessary movement of the locator and cap. The arms 122 and 123 are connected respectively to the plunger rod 125 of the

cylinder by means of links 126 and 130, respectively. The operating cylinder 124 is preferably mounted upon the flange 60 of the ram head, and is operated by a suitable solenoid valve controlled by the limit switch 2LS, carried preferably by the top plate 25 and actuated by means of an adjusting screw 117 carried by the arm 81 when it has moved upwardly to its maximum upper position, as hereinafter described. Movement of the cylinder plunger 125 is stopped by means of a stop screw 118 which is supported by the flange 60 and engageable with the arm 123. The limit switch 3LS is closed as the plunger reaches the limit of its movement.

The bucking cap 114 carries the bucking tool or anvil 131. Since the bucking tool is forced downwardly by the repeated downward movement of the drill ram 30 to place the rivet in the hole and to buck it up while being upset, the bucking cap is formed with an aperture 132 for the accommodation of the drill and/or countersink 84. A recess 133 is formed in the wall of the cap for the lateral passage of the drill and countersink. This permits the cap to be swung to and from its operative position without having to be moved the full axial length of the extending end of the drill and countersink. When the bucking tool is being moved downwardly to eject the rivet from the rivet locator and to its operative position, the lower end of the drill ram will be in engagement with the top surface of the cap. When the bucking tool is moved to the position just described by the drill ram, it is desirable to positively lock the drill ram in a position where it will support the bucking tool, without having to rely upon the drill ram operating cylinder 56. This is accomplished by a ram locking cam 134. This cam is carried by a shaft 135 mounted in suitable bearings 136 carried by the front plate 77 of the ram head. The cam is mounted in a suitable slot 140 formed in the wall of the cylindrical portion of the ram head through which it is movable into the cylindrical bore 26 thereof. The cam is so located that when the drill ram is moved to its bucking tool supporting position, the cam 134 can be moved inwardly to engage a detent surface 141 formed on the upper end of the ram. The cam 134 is operated by means of an operating cylinder 142, carried by the top plate 25 and connected to a cam lever 143 by means of links 144. The cam lever is secured to the shaft 135 which may thus be oscillated by the operation of the cylinder 142. The cylinder is operated by means of fluid supplied through a solenoid valve LV controlled, as hereinafter more fully described, by means of a limit switch 6LS. This switch is suitably located and is operated by means of an adjusting screw 137 carried by an extension 138 of the arm 81.

When the ram locking cam has reached its fully engaged position, and the drill ram is thereby ready to support the bucking cap and tool against axial movement, the riveting unit 23 is ready to be brought into action to upset the rivet, as hereinafter more fully described. In order to bring about the repeated and further operation of the riveting unit, a control switch 4LS is provided. This control switch is carried preferably on the inside of the front plate 77 of the ram head and is engaged by an adjusting screw 145 which is mounted upon an adjusting arm 146, rigidly carried by the cam shaft 135 (see Fig. 5). A stop arm 150 is formed on the cam lever 143 and is engageable with some fixed part of the ram head after the switch 4LS has been

operated, in order to limit any over travel of the cam operating cylinder 142.

The riveting unit of our invention is located at the forward end of the lower leg 20 of the 5 housing and comprises a ram housing 151 which is supported by and secured to the ram operating cylinder 152. This cylinder which is a standard article of manufacture is suitably connected to fluid under pressure controlled valves to be 10 hereinafter referred to.

The riveting ram 153 is slidably mounted within a suitable cylindrical bore 154 formed in the ram housing 151, and it is suitably connected to the plunger (not shown) of the ram operating 15 cylinder 152. The riveting ram is provided part way through its central portion with a cylindrical bore 156 which extends downwardly from the upper end thereof and within which is slidably mounted a switch plunger 160. This plunger is 20 provided with spaced tapered surfaces 161 and 162 for engagement with radially arranged bridge pins 163. These pins are slidably carried by the ram, and they are pushed outwardly by the inclined surfaces of the plunger when there is relative movement between the plunger and the riveting ram. A helical spring 164 is arranged at the bottom of the bore 156 and has its upper end engaging with the lower end of the switch plunger, whereby the plunger is normally held in its uppermost position. A bridge plate 165 is arranged on the outside of the ram and is connected to the bridge pins 163. A spring 166 at each end of the bridge serves to keep the same pressed inwardly toward the plunger and the rounded ends 35 of the pins in engagement with the coacting inclined surfaces of the switch plunger.

A rivet height control switch 9LS is mounted within the ram housing opposite the bridge plate 165 and is designed to be operated by this bridge 40 plate when the same is forced outwardly by the pins 163. Arranged preferably diametrically opposite the bridge plate is a cam plate 170 which is secured to the riveting cam. This plate is tapered and coacts with a pressure rail control 45 switch 7LS. This switch is operated by the cam plate when the riveting ram reaches the extreme positions of travel, as will hereinafter be more fully described.

Each of the switches 9LS and 7LS is carried 50 by a hinge arm 171 which has its lower end pivotally attached to a hinge block 172, carried by the housing. A leaf spring 173 tends to press the arms outwardly away from the ram. Each of the arms carries an adjusting screw 174 at its upper end which is forced by the spring 173 into 55 contacting an adjusting eccentric 175. The eccentric 175 for controlling the switch 9LS is carried by an adjusting knob 176, and the eccentric for adjusting the switch 7LS is carried by a knob 180. By rotating the knobs 176 and 180, the micro-switches 9LS and 7LS may be adjusted 60 to control the movements of the lower ram within narrow limits.

Also carried by the riveting ram 153 is a limit switch 8LS for coaction with the switch plunger 160 when the ram has been moved upwardly to support the workpiece against the presser foot 44. A switch pin 157 is slidably carried by the 70 ram, having one end engaging the switch 8LS and the other end engaging the tapered surface 162 of the plunger, whereby the switch will be operated by the initial relative movement of the ram and plunger. The contacts of the control switches 9LS, 7LS, and 8LS and the circuits in 75

which they are connected will be hereinafter described.

Mounted on top of the riveting ram is an anvil mounting disk 190 having ways 191 for the lateral reception of the base 192 of the riveting anvil 193. Suitable means (not shown) are provided for retaining the anvil in position upon the ram. Slidably mounted upon the riveting anvil for relative axial movement therewith is the pressure rail 194 of our device. The top surface 195 of this rail is normally maintained some distance above the top surface 196 of the anvil by means of a helical spring 200 mounted within the skirt 201 of the rail and seating upon an enlarged base portion 202 of the anvil. The enlarged base portion of the ram is formed with a diametrically arranged slot 203 through which is passed a trunnion shaft 204. This shaft carries a pressure rail stem 205 and it is secured to diametrically opposite sides of the skirt 201 of the pressure rail.

Carried at the upper end of the switch plunger 160 is a plunger stem 206 which is secured to the plunger in an adjustable manner and which has its upper end engaging with the pressure rail stem 205. Relative movement between the riveting ram and the switch plunger caused by the movement of the former during the riveting operation, causes the limit switch 9LS to be actuated to terminate the riveting operation at the predetermined point.

In carrying out our invention, certain solenoid valves and relays are employed in connection with the limit switches hereinbefore referred to. These valves and relays, as well as the switches, are standard articles of manufacture; and, since the detailed construction of these elements do not form a part of our invention, they are not shown or described in detail.

Reference is now to be had to Figs. 15 and 16, which are line drawings showing the various valves, switches, and electric circuits employed in carrying out our invention. The drill ram operating cylinder 56 and the cam operating cylinder 142 are provided with operating valves RV and LV, respectively. In like manner, the cylinder 124 for operating rivet locator and bucking tool cap is actuated by a valve LBV. A solenoid valve Q1 and a solenoid valve Q2 are provided for operating the lower ram upwardly and downwardly, respectively. Control relays 1CR, 2CR, 3CR, and 4CR are also provided for accomplishing certain functions, and these relays are provided with certain contacts to be described below. Electrical power lines are indicated at L1 and L2 which supply current to our device. In one of these lines, there is inserted a master switch 210 and a starter switch 211. A foot switch FS1 is provided which is to be depressed when the machine is to be put in operation. When the foot switch FS1 is depressed, current will flow, as will be clear from Fig. 15, through the contact A of double contact limit switch 8LS, through normally closed contact 4CRA of control relay 4CR and through the solenoid of valve Q1. This will cause fluid under pressure from a suitable source (not shown) to be supplied to the riveting ram operating cylinder to cause the riveting ram 153 to be initially elevated. As this plunger moves upwardly, the pressure rail 194 will be brought into contact with the under side of a workpiece positioned between the rail and the presser foot 44, causing the workpiece to be moved upwardly into contact with the presser foot. After the initial con-

tact of the workpiece with the presser foot, a slight amount of relative movement between the pressure rail and the anvil 196 will cause the limit switch 8LS to be moved from its contact 5 A to its contact B which will break the circuit through valve Q1, thereby terminating the initial upward movement of the riveting ram, and holding the ram in this position while drilling the workpiece. When switch 8LS is moved to its contact B, relay 3CR will be energized thereby closing normally open contacts 3CRA and 3CRB. Current now flows to solenoid valve RV through contact 3CRA and normally closed contact 1CRA of de-energized relay 1CR for operating the drill ram on its downward stroke by means of the operating cylinder 56. As the drill ram descends to drill and countersink the workpiece, normally open limit switch 1LS will be closed thereby energizing control relay 1CR. With the energization of this relay, the normally closed contact 1CRA thereof will be opened thereby interrupting current to the valve RV and stopping downward movement of the drill ram and causing the same to be elevated to its upper position. As soon as the drill ram starts its upward movement, switch 1LS is moved to its normally open position, but control relay 1CR is maintained in energized position through its contact 1CRB and sustained contact 3CRA of energized relay 3CR. As the ram reaches the uppermost end of its stroke, normally open limit switch 2LS is closed and current is thereby conducted through contact 1CRB closed by energized relay 1CR, and through control relay 2CR, thereby energizing this relay and closing its normally open contact 2CRA. Current will also flow through contact 3CRB of relay 3CR to energize solenoid valve LBV. This will cause the rivet locator 101 and the bucking tool 131 to be swung inwardly into coaxial relation with the drill ram. As the bucking tool and rivet locator reach their final operative positions, the normally open limit switch 3LS is closed which causes the solenoid valve RV to be again energized 35 thereby causing fluid under pressure to again flow to the cylinder 56 to again move the drill ram downwardly. This movement opens switch 2LS but solenoid LBV is maintained in energized position through contact 2CRA of relay 2CR. This circuit also energizes the circuit having in series the normally open limit switch 6LS and the latch valve LV. When the drill ram descends to the bottom of its stroke, switch 6LS will be closed thereby energizing solenoid valve LV to cause the cylinder 142 to be actuated thereby drawing locking cam 134 into position of engagement with the drill ram, and thereby temporarily holding it fixed against axial movement. When the locking cam has been drawn to its engaged position, normally open limit switch 4LS will be closed. This switch is normally in series with the A contact of limit switch 9LS and current will flow through these two switches and through normally closed contact 4CRA of relay 4CR to again energize solenoid valve Q1. Fluid under pressure will thereby again flow to the actuating cylinder of the riveting ram, causing the ram with its riveting anvil to be moved upwardly. Since further upward movement of the pressure rail 194 is prevented by contact with the workpiece, relative movement between the anvil and the pressure rail will be brought about. This movement will be transmitted by the switch plunger 160 to the bridge 165 which will cause the limit switch 9LS to be operated from its con-

tact A to its contact B at the instant the rivet head has reached its predetermined height and thus terminate the riveting operation. When the riveting operation has been completed and contact B of switch 9LS is closed, solenoid valve Q2 will be energized through normally closed limit switch 7LS. This will cause the riveting ram to move downwardly, and when the lower position has been reached, further movement is interrupted by the opening of limit switch 7LS. Current flowing through 4LS and 9LSB will also energize relay 4CR thereby closing its normally open contact 4CRB which is necessary in order to maintain a live circuit through 7LS and to complete the lowering movement of the riveting ram since the circuit through 4LS and 9LSB is broken during the initial downward travel of the riveting ram by movement of limit switch 9LS from its contact B to its contact A and the release of the lock cam on the drill ram. Should it be desired to operate the solenoid valve Q2 to retract the riveting ram beyond the position where it is interrupted by the switch 7LS, the valve Q2 may be energized separately and independently by closing foot switch FS2. Release of the foot switch FS1 interrupts the operation of the machine instantly.

While our device is normally to be used to perform all of the above mentioned operations automatically and in sequence with each other, it may sometimes be desired to use the machine for riveting only or for drilling only. In order to accomplish this, I employ a selector switch 212, shown in Fig. 16. This switch has three groups of contacts 213, 214, and 215, which may be independently operated to bring about certain circuit arrangements. In Fig. 16, I have shown the contacts of this switch in the three positions required for accomplishing the three results above mentioned. Arrangement 220 is for full automatic; arrangement 221 is for riveting only; and arrangement 222 is for drilling only. In Fig. 16, the use of the letter "X" indicates that that particular contact is closed, whereas the use of the letter "O" indicates that the contact so identified is open. As shown, when the device is to be fully automatic in operation, contact 1SSB only is closed, contacts 1SSA, 1SSC, and 1SSD remaining open. When the machine is to be used for riveting only, contacts 1SSA and 1SSB are closed. Contact 1SSD only is closed when the machine is to be used only for drilling.

What is claimed is:

1. A riveting machine comprising a drill ram, a riveting ram, a drill carried by said drill ram, means for supporting the workpiece while being drilled, means operable substantially in synchronism with contact of the workpiece with the supporting means to operate the drill ram to drill the workpiece, means for returning the drill ram at the completion of the drilling operation, a laterally movable locator for yieldably holding a rivet, a laterally movable bucking tool, means for moving said locator and said bucking tool into coaxial relation with each other and disposing them in between said drill ram and the workpiece, means for bringing said drill ram into cooperative relation with said bucking tool to eject the rivet and to feed it into the drilled hole, means for locking said drill ram in position to support said bucking tool, and means carried by said riveting ram and cooperating with said bucking means to effect a riveting operation.

2. A riveting machine comprising a drilling unit, and a riveting unit, said drilling unit com-

prising a head formed with a cylindrical bore, a drill ram mounted within said bore for axial movement therein, operating means for reciprocating said ram, said ram being formed with an abutment, an adjustable stop carried by said head and engageable with said abutment to limit the downward travel of said ram, a drill rotatably carried by said ram, a bucking tool interposable between said ram and a workpiece for engagement with the head of a rivet carried by the workpiece, means for locking said ram in its position of engagement with said bucking tool, and riveting means carried by said riveting unit for cooperation with said bucking tool to effect a riveting operation.

3. A riveting machine comprising a drilling unit, and a riveting unit, said drilling unit comprising a reciprocating drill ram, a drill carried by said ram for drilling a rivet hole in a workpiece, operating means for moving said ram to upper and lower predetermined limits, a bucking tool interposable between said ram and the workpiece, means operable by said ram at the lower extremity of movement during its initial operation to interrupt the downward movement and to actuate said operating means to elevate said ram, means operable by said ram at the upper extremity of movement to move said bucking tool to a position of cooperation with the ram, means operable in synchronism with the movement of the bucking tool to cause the ram to descend a second time to engage and axially support the bucking tool, and means operable subsequently to the second movement of said ram to operate the riveting unit to cooperate with the bucking tool to effect a riveting operation.

4. A riveting machine comprising a drilling unit, and a riveting unit, said drilling unit comprising a reciprocating drill ram, a drill carried by said ram for drilling a rivet hole in a workpiece, operating means for moving said ram to upper and lower predetermined limits, a bucking tool interposable between said ram and the workpiece, means operable by said ram at the lower extremity of movement during its initial operation to interrupt the downward movement and to actuate said operating means to elevate said ram, means operable by said ram at the upper extremity of movement to move said bucking tool to a position of cooperation with the ram, means operable in synchronism with the movement of the bucking tool to cause the ram to descend a second time to engage and axially support the bucking tool, means for locking said ram in its tool-supporting position, and means operable subsequently to the second movement of said ram to operate the riveting unit to cooperate with the bucking tool to effect a riveting operation.

5. A riveting machine comprising a drilling unit, and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for initially actuating said operating means to bring said rail to workpiece supporting position, means carried by said riveting ram for interrupting the movement of said rail in said initial position, means operable substantially upon contact of the workpiece with said rail to actuate said rail ram and subsequently to position said bucking tool, and means operated subsequently to the posi-

11

tioning of the bucking tool to resume the actuation of the riveting ram to effect a riveting operation.

6. A riveting machine comprising a drilling unit, and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for initially actuating said operating means to bring said rail to workpiece supporting position, means carried by said riveting ram for interrupting the movement of said rail at said position, means operable substantially upon contact of the workpiece with said rail to actuate said drill ram, means for returning said drill to its upper position at the completion of the drilling operation, means actuated in synchronism with the upwardly moving drill ram to position said bucking means coaxial therewith, control means actuated by the movement of the bucking means for causing the drill ram to move downwardly to engage said bucking means, and means operated synchronously with the placing of the bucking means to resume the actuation of the riveting ram to effect a riveting operation.

7. A riveting machine comprising a drilling unit, and a riveting unit, said drilling unit comprising a reciprocating drill ram having a drill, and a bucking tool cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for actuating said operating means to bring said rail to workpiece supporting position, means carried by said riveting ram for interrupting the movement of said rail at said position, means operable substantially upon contact of the workpiece with said rail to actuate said drill ram, means for returning said drill ram to its upper position at the completion of the drilling operation, means actuated in synchronism with the upwardly moving drill ram to position said bucking tool coaxial therewith, control means actuated by the movement of the bucking tool for causing the drill ram to move downwardly to engage said bucking tool, means for locking said drill ram in its tool-engaging position, and means operated synchronously with the placing of the bucking tool to actuate the riveting ram to effect a riveting operation.

8. A riveting machine comprising a drilling unit and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for initially actuating said operating means to bring said rail to workpiece supporting position, means carried by said riveting ram for interrupting the movement of said rail at said initial position, means operable substantially upon contact of the workers with said rail to actuate said drill ram and to position said bucking means, means operated subsequently to the drilling operation to actuate the riveting ram a second time to effect a riveting operation, and means operable

12

by the relative axial movement of said rail and said riveting anvil to interrupt the operation of the latter when the rivet head has been upset the predetermined amount.

9. A riveting machine comprising a drilling unit and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for actuating said operating means to bring said rail to workpiece supporting position, a limit switch carried by said riveting ram, an operating member carried by said riveting ram and engageable with said limit switch for locating said pressure rail against a workpiece, means operable substantially upon contact of said rail with a workpiece to actuate said drill ram, and means operated subsequently to the drilling operation to actuate the riveting ram to effect a riveting operation.

10. A riveting machine comprising a drilling unit and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for actuating said operating means to bring said rail to workpiece supporting position, a limit switch carried by said riveting ram, an operating member carried by said riveting ram and engageable with said limit switch for interrupting the movement of said rail when said rail is in bearing contact with a workpiece, means operable substantially upon contact of said rail with a workpiece to actuate said drill ram, means operated subsequently to the drilling operation to actuate the riveting ram to effect a riveting operation, a rivet height switch carried by said pedestal and operable subsequently to the drilling operation, and actuating means carried by said riveting ram for operating said last mentioned switch to cause the movement of the riveting ram to be interrupted when the rivet has been upset the predetermined amount.

11. A riveting machine comprising a drilling unit and a riveting unit, said drilling unit comprising a reciprocating drill ram having a drill, and bucking means cooperating with said drill ram, said riveting unit comprising a pedestal, a riveting ram slidably carried by said pedestal, operating means for said riveting ram, an anvil carried by said riveting ram, a spring pressed pressure rail slidably carried by said anvil, means for actuating said operating means to bring said rail to workpiece supporting position, a limit switch carried by said riveting ram, an operating member carried by said riveting ram and engageable with said limit switch for interrupting the movement of said rail when said rail is in bearing contact with a workpiece, means operable substantially upon contact of said rail with a workpiece to actuate said drill ram, means operated subsequently to the drilling operation to actuate the riveting ram to effect a riveting operation, a rivet height switch carried by said pedestal and operable subsequently to the drilling operation, actuating means carried by said riveting ram for operating said last mentioned

13

switch to cause the movement of the riveting ram to be interrupted when the rivet has been upset the predetermined amount, means operable at the completion of the riveting operation for returning said riveting ram, and switch means for interrupting the downward movement thereof.

THOMAS H. SPELLER.
